(57) **CLAIM**

We claim the ornamental design for a spectrophotometer, as shown and described.

DESCRIPTION

FIG. 1 is a front, top and left side perspective view of a spectrophotometer showing our new design;
FIG. 2 is a front elevational view thereof;
FIG. 3 is a rear elevational view thereof;
FIG. 4 is a top plan view thereof;
FIG. 5 is a bottom plan view thereof;
FIG. 6 is a left side elevational view thereof; and,
FIG. 7 is a right side elevational view thereof.
The broken lines shown are for illustrative purpose and form no part of the claimed design.
